UNITED STATES PATENT OFFICE.

ARTHUR C. WITMAN, OF COLUMBUS, OHIO.

GAS-STOVE.

SPECIFICATION forming part of Letters Patent No. 754,180, dated March 8, 1904.

Application filed August 26, 1903. Serial No. 170,850. (No model.)

To all whom it may concern:

Be it known that I, ARTHUR C. WITMAN, a citizen of the United States, residing at Columbus, in the county of Franklin and State of Ohio, have invented a certain new and useful Improvement in Gas-Stoves, of which the following is a specification.

This invention relates to gas-stoves, and is particularly designed to provide an improved burner and back to be incased within a suitable stove-body or within a fireplace. It is furthermore designed to provide an exceedingly simple construction for convenience in setting up and taking apart the stove, while at the same time insuring an effective combustion of the gas to secure the maximum heating effect.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view of a burner and fireback embodying the features of the present invention. Fig. 2 is a vertical sectional view thereof. Fig. 3 is a cross-sectional view on the line 3 3 of Fig. 2. Fig. 4 is a detail perspective view of one of the end plates for the expansion-chamber. Fig. 5 is a detail view of the mixer.

Like characters of reference designate corresponding parts in each and every figure of the drawings.

In carrying out the present invention it is designed to have the device made up of few parts, and therefore it has been found convenient to employ sheet metal for the greater part of the device; but it will of course be understood that it is not desired to limit the invention to this material, as the parts hereinafter described as formed of sheet metal may be cast without altering the construction of the device or affecting the invention in any manner whatsoever.

As best illustrated in Fig. 2 of the drawings, it will be seen that the present device embodies an expansion-chamber 1, which is substantially L-shaped in cross-section, or, in other words, has a forward base extension 2. 55 As hereinbefore indicated, this expansion-chamber is preferably formed from a single sheet of metal, which is bent to form the bottom 3 of the chamber, the back 4, and the top 5. The bottom is projected somewhat in front of the top 5, is then bent upwardly to form a front 6, and thence rearwardly to form a burner-plate 7, which is pierced throughout its area by perforations 8, through which the gas is adapted to escape in the form of flames. 65 It will here be noted that the front 6 is about one-third of the height of the back 4, and the extension 2 of the chamber is embraced between the burner-plate 7, the front 6, and the adjacent portion of the bottom 3. From the 70 front edge of the top 5 the plate is extended upwardly to form the fireback 9, the top edge of which is cut away intermediately for a considerable extent, as indicated at 10, to permit the products of combustion to pass over the top of 75 the back. The opposite ends of the back 9 are bent to form wings or flanges 11, projected in front of the back and lying above the expansion-chamber. The open front portion of the expansion-chamber between the top of said 80 chamber and the burner-plate 7 is closed by means of a plate 12, the upper edge of which overlaps the fireback 9 and is connected thereto by means of suitable fastenings 13—as, for instance, rivets. For connecting the fireback 85 member 12 to the burner-plate 7 the rear edge of the burner-plate is bent upwardly to form a flange 14, and the plate 12 rests upon the plate 7 and against the flange 14, to which it is connected by means of rivets or other suitable fastenings 15. From the foregoing description it 90 will be noted that with the exception of the plate 12 all of the hereinbefore described parts are formed from a single sheet of metal, and it will now be understood that these parts 95 may be cast as well as bent from a metallic sheet without affecting the invention in any manner whatsoever.

For closing the ends of the expansion-chamber opposite plates or end pieces 16 are em- 100

ployed, and as these plates are duplicates in construction and arrangement a description of one of the plates is deemed sufficient. Each of these plates is substantially L-shaped or 5 provided with a front base extension 17, so as to correspond with the cross-sectional shape of the expansion-chamber. Upon the inner face of the end plate there is a marginal flange 18, which extends entirely around the plate 10 at a predetermined distance inwardly from the edge thereof so as to engage the inner sides of the top 5, back 4, bottom 3, front 6, burner-plate 7, and the fireback-plate 12, so as to prevent edgewise displacement of the 15 end plate and at the same time brace and stiffen the expansion-chamber. By reference more particularly to Figs. 1 and 2 it will be seen that the front edge portion of the end plate above the part 17, as indicated at 19, 20 projects in front of the fireback to the same extent as do the flanges 11 of said fireback, so as to partially inclose the space immediately in front of the fireback for the purpose of confining the flames therein. The opposite 25 end plates 16 are connected by a tie-rod 20, the head of which is countersunk within a socket 21, projected at the inner side of one of the plates, while its opposite end is provided with a nut let into a socket 22 in the 30 other plate, whereby the end plates are held in position without the employment of other fastenings. Each end plate is furthermore provided with a lug, ear, or projection 23 upon the part 19 of the plate and designed to 35 lie against the front of the lower fireback member 12 so as to embrace the latter between the ear and the adjacent portion of the flange 18 on the end plate.

Gas is admitted to the expansion-chamber 40 through an elbow 24, which pierces the back of the chamber, near the top thereof, there being a suitable service-pipe 25 connected to the elbow and also connected to a suitable source of supply. (Not shown.)

45 For mixing the required amount of air with the gas the two service-pipe sections which are next to the elbow 24 are joined by a coupling 26, having a longitudinal opening 27 in each side and provided with set-screws 28 for 50 engagement with the respective pipe-sections to hold the coupling or mixer against accidental displacement. It will of course be understood that the pipe-sections 25 are separated by a suitable interspace, with which the 55 openings 27 of the mixer communicate and through which air is drawn inwardly by the flow of gas, whereby the required mixture is admitted to the upper portion of the expansion-chamber. The advantage of the elbow 60 24 is that it may be turned for connection with a service-pipe without respect to the relation of the latter.

It has not been deemed necessary to show the device of the present invention fitted within 65 a stove-casing, as the construction and opera-

tion of the device will be clearly understood without such illustration. In this connection it will of course be understood that the ears 29 at the top of the fireback 9 are designed for connection with the top of a stove-casing, 70 whereby the opening 10 forms an exit for the passage of the products of combustion to the flue of the casing. Moreover, the flanges 11 and 19 are also employed in connecting the device to the sides of the stove.

75 When the present form of stove is in use, the gas and air enter the upper portion of the expansion-chamber, and in passing downwardly and forwardly to the perforations of the burner-plate the mixture becomes heated 80 and expanded to the proper degree for the most effective combustion at the burner-plate 7, as the front portion 12 of the chamber is maintained in a highly-heated condition by the flames issuing through the perforations of 85 the burner-plate.

While not shown, I contemplate facing the fireback members 9 and 12 with asbestos in the usual manner.

Having thus described the invention, what 90 is claimed, and desired to be secured by Letters Patent, is—

1. A gas-stove embodying an expansion-chamber having a fuel-inlet, and provided with a base extension, the top of which is provided 95 with burner-openings and has at its rear end an upstanding flange, the front of the chamber between the flange and the top thereof being open, an integral fireback member rising from the front of the top of the chamber, 100 and a lower fireback member closing the open front of the expansion-chamber and connected at its upper end to the upper fireback member and at its lower end to the flange on the extension of the chamber.

105 2. A gas-stove embodying an expansion-chamber having a base extension, the top of such extension having openings to constitute a burner-plate, a fireback rising from the front of the top of the chamber, end plates 110 applied to opposite ends of the chamber, and a removable tie-rod extending through the chamber and piercing the respective end plates.

115 3. A gas-stove embodying an expansion-chamber having a base extension, the top of the extension having openings to constitute a burner-plate, a fireback rising from the front of the top of the chamber, end plates applied to opposite ends of the chamber to close the 120 same and provided with marginal flanges fitting the ends of the chamber, and a removable tie-rod lying within the chamber and piercing the end plates.

125 4. A gas-stove embodying an expansion-chamber having a base extension, the upper front portion of the chamber between the extension and the top being open, the top of the extension having openings to constitute a burner-plate, a lower fireback member clos- 130

ing the open front portion of the chamber between the burner-plate and the top of said chamber, an upper fireback member rising from the front of the top of the chamber and 5 provided at opposite sides with forwardly-directed flanges, end plates applied to and closing the ends of the chamber and also pro-

jected in front of the chamber above the burner-plate, and a tie-rod within the chamber and piercing the end plates.

ARTHUR C. WITMAN.
